CLAIM

The ornamental design for a connector for elongated ceiling grid members as shown and described.

DESCRIPTION

FIG. 1 is a front, right-side, top perspective view of a connector for elongated ceiling grid members showing the new design;

FIG. 2 front elevational view thereof, the rear elevational view being a mirror image of the front elevational view;

FIG. 3 is a left-side elevational view thereof, the right-side elevational view being a mirror image of the left-side elevational view;

FIG. 4 is a top plan view thereof;

FIG. 5 is a bottom plan view thereof; and,

FIG. 6 is a cross-sectional view taken along line 6-6 shown in FIG. 4.
